F. ORTLIEB

SCISSORS SHARPENER

Original Filed Aug. 9, 1926

Patented Feb. 21, 1928.

1,660,206

UNITED STATES PATENT OFFICE.

FREDERICK ORTLIEB, OF CATASAUQUA, PENNSYLVANIA.

SCISSORS SHARPENER.

Application filed August 9, 1926, Serial No. 128,255. Renewed January 12, 1928.

My present invention relates to improvements in scissors' sharpeners which, while adapted for use in sharpening various bevel-edge tools or instruments, is particularly designed for use by barbers and other engaged in the tonsorial art, where it is essential that the tools or instruments be maintained at all times in best condition for efficiency and accuracy.

10 The primary object of the invention is the provision of a tool sharpening device of this character and adapted for manual operation, which is simple in construction and operation, inexpensive in the cost of manufacture, and may be manipulated with facility for fashioning the correct bevel cutting edge on scissors or other instruments or tools. To this end the invention contemplates essentially, a work holder and a tool holder, the latter adapted for manual operation with relation to the work in the stationary work holder, and in certain novel combinations and arrangements of parts involving these structures as will hereinafter 25 be more fully pointed out and claimed.

In the accompanying drawings I have illustrated one complete example of the physical embodiment of my invention as applied for the purpose of sharpening scissors, in 30 which the parts are combined and arranged according to one mode I have thus far devised for the practical application of the principles of my invention.

Figure 1 is a view in side elevation of 35 the device of my invention illustrating a scissors blade in position to be sharpened.

Figure 2 is a top plan view of the device of Figure 1 with the scissors blade omitted for convenience of illustration.

40 Figure 3 is an end elevation of the device showing the scissors in position for sharpening a blade.

Figure 4 is a detail sectional view of the work holder.

45 In order that the utility, general assembly and arrangement of parts may readily be understood I have shown in Figure 3 a pair of scissors S of which the bevel-edge blade B is to be sharpened. In carrying out 50 my invention I preferably use a supporting frame which may rest upon the lap of the person sharpening the scissors, on a table, or other suitable support, and the supporting frame is composed of a base plate 1 having a 55 transversely disposed arm 2 secured thereto

as by rivet 3, and the base-arm and plate are of sufficient width and length to form a stable support for the sharpening device.

At one end the base plate is fashioned with an upright post 4 and at the upper end of 60 the post a cross arm 5 is rigidly fixed to form a rest for the tool holder, which as will be explained, is manually reciprocated with a suitable tool transversely of the 65 blade B.

At the opposite end of the base plate 1 a bent, shorter post 6 is fashioned, preferably integral with the plate, and the upper portion of the post which is parallel with the post 4 is widened to form a head 7. The 70 top edge 8 of this head is cut away or beveled to form a beveled face 9, and this head with its beveled face performs the function of an anvil for the scissor blade B, which latter is seated on the anvil as indicated in 75 Figure 1. As seen in Figure 4 the upright portion of the post 6 is fashioned with a vertical, central slot 10 by means of which a generally U-shaped yoke of the work holder is adjustably attached to the post. 80

The U-shaped yoke is preferably fashioned of resilient metal with an attaching plate 11, which at its upper end is provided with a widened head 12 complementary to the fixed head 7 of the post 6, and the upper edge 13 of this head 12 forms a rest for the scissor blade B in combination with the anvil head 7 of the post. 85

The yoke is fashioned with complementary bolt or screw holes to accommodate a clamping screw or bolt 14 having its head countersunk in the outer portion of the yoke and passing through the hole in the plate 11, also passes through the slot 10 of the post 6. By means of a wing nut 15 the yoke may be 90 clamped in adjusted position with relation to the post 6 with the attaching plate 11 and its head in closed frictional contact with the post 6 and its head 7. By properly adjusting the yoke the work holder may be adapted 95 for use with blades of various widths, the slot 10 being of sufficient length to permit the vertical adjustment of the yoke of the 100 work holder.

At its upper end the outer arm of the yoke 105 is fashioned with a head 16 which curves toward and over the upper edge 13 of the yoke-head 12, and as the metal of the yoke is resilient, it will be apparent that the wing nut 15, when turned on its bolt, not only holds 110

the yoke rigid, but the nut also clamps the resilient head 16 with its edge 17 against the outer face of the scissor blade B. Thus the scissor blade may be slipped into position 5 on its anvil between the bevel face 9 and the edge 17, and then the wing nut is turned to rigidly clamp the blade in the work holder as shown in Figure 1. The blade is clamped in position with its beveled cutting edge arranged for sharpening, and the tool holder that it manually reciprocated is moved through the same plane as that of the beveled edge.

The tool holder comprises an arm 18 and 15 a clamp-head 19, the latter of U-shape, and provided with a clamping screw or bolt 20. At 21 the clamp-head is fashioned with a slot with its lower wall forming an extension and flush with the upper face of the lower 20 jaw of the clamp head, and a file as 22 (here shown as the working tool) is secured by the bolt 20 in the head. The file is slipped through the slotted head with its lower face resting on the upper face of the lower jaw 25 of the head, and the screw or bolt 20 is used to clamp the file rigidly in the slotted head. If desired, the file may be removed, and an abrading stone may be clamped in the head by means of the bolt 20, or other suitable tool 30 may be secured in the head 19.

The rear end of the arm 18 is supported on the rest 5 and at its front end the tool holder is supported by means of the file on the scissor blade B. The height of the rest 35 and of the work-holding head are so related that the tool-holder is preferably inclined as indicated in Figure 1, but in all cases, the lower face of the file that contacts with the blade to be sharpened is parallel with the

beveled edge of the blade. Thus the file holder or tool holder, supported as shown may manually be reciprocated while supported on the rest and the blade to sharpen the latter, and the desired pressure may be imposed on the tool-holder by the hand. The 45 file may move transversely at right angles to the blade, or it may be moved diagonally across the blade if desired, and it is moved longitudinally of the blade and rest as the sharpening progresses in order that the full 50 length of the blade may be sharpened. It will be apparent that after the work-holder and tool-holder have been properly set, the latter may be reciprocated with relation to the stationary work holder and the blade 55 sharpened with accuracy and facility.

Various types of files may be used, and various types of abrading tools may be used in the head of the tool-holder, and other changes may be made in the illustrated device, within the scope of my appended 60 claim, without departing from the principles of my invention.

Having thus fully described my invention, what I claim as new and desire to secure 65 by Letters Patent is—

In a work holder the combination with a slotted, fixed head having a beveled face, of a vertically adjustable U-shaped yoke having an attaching plate for co-action with 70 said slotted head, said yoke having a resilient clamping head for co-action with the fixed head, a clamping bolt connecting said yoke and fixed head, and a clamping nut for the bolt.

In testimony whereof I have affixed my signature.

FREDERICK ORTLIEB.
